US00D788101S

(12) **United States Design Patent** (10) Patent No.: **US D788,101 S**
(45) Date of Patent: **** May 30, 2017**

(54) **ELECTRONIC DEVICE**1/0214; H04M 1/0279; H04M 1/0281;
H04M 1/0283; H04M 1/72544(71) Applicant: **Intel Corporation**, Santa Clara, CA
(US)

See application file for complete search history.

(72) Inventors: **Douglas Satzger**, Santa Clara, CA
(US); **Sameer Sharma**, Santa Clara, CA (US); **Gadi Amit**, San Francisco, CA (US); **Yoshikazu Hoshino**, San Francisco, CA (US)(73) Assignee: **Intel Corporation**, Santa Clara, CA
(US)(**) Term: **14 Years**(21) Appl. No.: **29/513,138**(22) Filed: **Dec. 27, 2014****Related U.S. Application Data**

(63) Continuation of application No. 29/464,887, filed on Aug. 21, 2013.

(51) LOC (10) Cl. **14-02**

(52) U.S. Cl.

(57) **CLAIM**

The ornamental design for an electronic device, as shown and described.

DESCRIPTION

FIG. 1 is a perspective view of an electronic device according to our new design;

FIG. 2 is a front view thereof;

FIG. 3 is a back view thereof;

FIG. 4 is a side view thereof;

FIG. 5 is another side view thereof;

FIG. 6 is a top view thereof; and,

FIG. 7 is a bottom view thereof.

The broken lines of the FIGURES represent portions of the electronic device that form no part of the claimed design.
